UNITED STATES PATENT OFFICE.

WALTER W. SIBSON AND THOMAS ALLSOP, OF PHILADELPHIA, PENNSYLVANIA, ASSIGNORS TO THE PHILADELPHIA DRYING MACHINERY COMPANY, OF PHILADELPHIA, PENNSYLVANIA, A CORPORATION OF PENNSYLVANIA.

CIRCULATING DYEING-MACHINE.

1,072,682.

Specification of Letters Patent.

Patented Sept. 9, 1913.

Application filed January 18, 1911. Serial No. 603,229.

To all whom it may concern:

Be it known that we, WALTER W. SIBSON and THOMAS ALLSOP, of Philadelphia, in the county of Philadelphia and State of Pennsylvania, have invented certain new and useful Improvements in Circulating Dyeing-Machines, whereof the following is a specification, reference being had to the accompanying drawings.

10. The invention relates to dyeing machines, and more particularly to machines of the open vat type, where the dye liquor is caused to circulate through the vat by mechanical means.

15. An object of the invention is to provide means for supporting the material or articles under treatment in a plurality of layers, extending transversely to the direction of flow of the dye liquor, thus accomplishing a complete presentation of the material or articles to the dye liquor, especially when large quantities of material or a large number of articles are under treatment at the same time; and a further object is to provide 20 means whereby access may be had to any one of said layers without disturbing or removing the other layers from the supporting cage or basket.

25. A further object of the invention is to provide propellers for circulating the dye liquor, which are so disposed that said dye liquor shall with certainty be caused to flow in a direction parallel with the vat as it leaves the propeller chamber, so that all 30 portions of the material or articles being treated, shall be subjected to an equal flow of the dye liquor; and a further object is to dispose the propellers so that one propeller will neutralize or balance the thrust of the other propeller, whereby the power required 35 to operate the same may be reduced to a minimum.

40. A still further object of the invention is to provide means, whereby the operating mechanism for the propellers may be completely housed from the dye liquor; and also means whereby access to said propellers may be readily had for cleaning or clearing the propellers from any material which may collect in the propeller chamber, and thus interfere with the proper circulation of the dye liquor.

45. These and other objects will in part be

obvious, and will in part be hereinafter more fully described.

5. In the drawings which show by way of illustration one embodiment of the invention, Figure I, is a part plan view and part sectional view of a dyeing machine, embodying our improvements. Fig. II, is a vertical sectional view longitudinally through the dyeing machine. Fig. III, is a sectional view on the line III, III, of Figs. I, and II. Fig. IV, is a detail sectional view of the hand wheel and clutch for controlling action 60 of the valves. Fig. V, is a side elevation of the cage or basket removed from the dyeing machine, and with certain of the partitions and closing doors released and swung to open position. Fig. VI, is a sectional view on the lines VI, VI, of Fig. V. Fig. VII, is a perspective view of one of the supporting cleats for the hinged partitions or closing members.

65. Referring in detail to the drawings, the machine consists of a vat 1, which may be of any approved construction, but which as is herein shown, is rectangular and comprises side and end walls. Adjacent to one end of the vat is a chamber 2, which is 70 formed by a cross partition 3, extending from side to side of the vat, and a similar cross partition 4, which is spaced from the end wall 5, of the vat so as to form a passage between the end wall and the cross partition 75 4, which extends from the bottom to the top of the vat. Said partitions 3, and 4, terminate short of the bottom and the top of the vat.

70. The propeller chamber 2, is partly closed 80 by a bottom board 6, which extends from end to end of the propeller chamber, but which extends only part way to the side partition 3, of the propeller chamber, thus forming a discharge passage or opening 7. The 85 propeller chamber is similarly closed at the top by a board or plate, which extends only part way to the partition 3, thus forming a discharge passage or opening 8, at the upper side of the propeller chamber. The 90 valve 9, is hinged to the bottom board or plate 6, at 10, and serves as a means for closing the discharge opening 7. As above noted the partitions 3, and 4, are spaced from the bottom of the vat so as to form a passage 10. 11, which connects the passage between

the end wall 5, and the side wall 4, of the compartment with the main portion of the vat.

The valve 9, is so disposed that when lowered so as to open the discharge passage 7, said valve engages the bottom of the vat and will close the passage 11, leading to the passage or compartment at the end of the vat. The cover plate or support 12, extends across the top of the vat directly over the propeller chamber, and is spaced from said partitions 3, and 4, so as to form a passage 13, between the cover plate 12, and the plate or board, covering the top of the propeller chamber. A valve 14, closes the discharge opening 8, when the parts are in the position shown in Fig. II, and when said valve 14, is opened, the outer edge of the valve will engage the cover or support 12, and close the passage 13. Valves 9 and 14, when in open position, serve not only to close the passage in rear of the valves, but also form deflectors which aid in the even circulation of the dye liquor.

25 The valves 9, and 14, are connected by a link 15, which is of such length that when one of said valves is closed the other is held in open position. The upper valve is pivoted at its outer face to a link 16, which extends through a suitable opening in the cover plate and is slidably and pivotally connected with one end of a rock arm 17. The rock arm 17, is pivoted to a bracket 18, on the supporting plate 12. As a means for manipulating the rock arm 17, so as to periodically close one valve and open the other, we have provided a shaft 19, which is journaled in suitable brackets 20, mounted on the cover plate 12. Said shaft may be driven in any desired way, as by a sprocket wheel 21. A worm 22, is mounted on said shaft 19, and engages a worm wheel 23, mounted on an inclined shaft 24, journaled in a suitable bracket 25, on the cover plate 12. Said inclined shaft 24, carries a worm 26, which meshes with a worm wheel 27, on a countershaft 28. The countershaft 28, is journaled in suitable bearings carried by the bracket 25. On the outer end of the countershaft 28, is a cam 29, which is formed with a concentric portion 30, and a flat substantially radial portion 31.

The rock arm 17, extends inwardly from the supporting bracket 8, and is deflected laterally so as to form a flat face adapted to engage the flat face 31, on the operating cam 29. The object in forming the cam 29, with the flat face and said rock arm with a correspondingly flat engaging face, is to 60 provide a quick shifting of the valves when said parts are in proper position to bring about such shifting.

When the parts are positioned as shown in Fig. II, the valve 14, is closed and the 65 valve 9, is open, so that the discharge from

the propeller chamber would be through the discharge opening 7, underneath the cage containing the material to be dyed, upwardly through the cage and thence through the passage 13, to the passage at the end of the vat between the side wall 4, of the propeller chamber, and the end wall 5, of the vat. As the shaft 19, is rotated, the worm 22, will accordingly turn the inclined shaft carrying the worm wheel 23, which will in turn slowly rotate the worm wheel 28, and the shaft 29. By a comparatively slight movement of the countershaft 28, the flat face 31, on the cam 29, will throw the rock arm 17, so as to raise the valve 14, opening the discharge passage 8, and close the valve 9, thereby closing the discharge passage 7. The concentric portion 30, of the cam will hold said rock arm with the valve in this position until such concentric portion passes from contact with the rock arm after which the valves and connected parts will at once cause the valve 14, to close and the valve 9, to open.

When the valve 14, is open, the dye liquor will be discharged through the passage 8, above the cage containing the material to be dyed, downwardly through the cage, underneath the cage, and thence through the passage 11, to the passage way between the end wall 5, of the vat and the side wall 4, of the propeller chamber.

Adjacent to each end of the propeller chamber is an opening 32, which leads from the passage at the end of the vat into the propeller chamber, thus forming an intake for the propeller chamber. A partition 33, extends across the propeller chamber adjacent each intake and is formed with a circular opening in each of which is mounted a propeller.

The propeller 34, is secured to a shaft 35, which is journaled at 36, in a bearing attached to the end wall of the propeller chamber and at its opposite end said shaft extends through a suitable stuffing box 37, see Fig. III, formed in the side wall of the vat. On the outer end of the shaft is a sprocket wheel 38, which is connected by a chain 39, with a large sprocket wheel 40, mounted on the shaft 19. The propeller 41, is located adjacent the intake at the other end of the propeller chamber and is also rigidly attached to the shaft 35. As the shaft 19, rotates, the shaft 35, will be also rotated through the sprocket chain connection and the propeller constantly rotated in the same direction with the shaft 35. The propeller causes an inflow of the dye liquor from the passage at the end of the vat through the intakes 32, at the ends of the propeller chamber.

The propellers are oppositely disposed and therefore the thrust of one propeller will neutralize the thrust of the other, so that the power required to rotate the propeller 130

propellers is reduced to a minimum. Also by the disposition of the propellers as herein shown and described, we are able to cause a flow of the dye liquor in a direction lengthwise of the vat and substantially throughout the entire width thereof, so that all portions of the material to be dyed will be subjected to a substantial uniform flow of the dye liquor.

10 It will readily be understood that by the above mechanism, we are able to provide a continuous flow of the dye liquor through the dye cage holding the material to be dyed, and that the direction of the flow is controlled by the valves 9, and 14. It will also be obvious that by the mechanism herein shown and described, the valves can be automatically shifted periodically so as to change the direction of flow.

20 The inclined shaft 24, see Fig. IV, is splined to a hand wheel 42, while the worm wheel 23, is loose on said shaft. Said worm wheel carries clutch members 43, which engage with clutch members on the hand 25 wheel. By sliding the hand wheel 42, on its splined connection with the inclined shaft we may disengage said clutch members, so that said gear 23, will run free on said inclined shaft. A locking bolt 44, may 30 be used for holding said hand wheel 42, with the clutch members disengaged. By this means, we are able to release the valves from their operating mechanism, so as to cause the flow to be continuous in one direction or the other.

35 Extending entirely across the vat and from the partition 3, to the wall at the other end of the vat, is a slotted bottom board or grid 46, which is located substantially at the 40 lower edge of the partition 3, and spaced from the bottom of the vat so as to form a circulating passage underneath the same. This slotted grid may be employed as a convenient adjunct in some kinds of work as it 45 tends to cause an even flow of the dye liquor through the portion of the vat containing the cage in which is placed the material to be dyed. We do not, however, wish it to be understood that the use of such grid is essential to any features of our invention.

50 The basket 47, for supporting the material to be dyed as herein shown, consists of side and end walls which may be of any desired construction, and secured together in any well known way. Said cage or basket is 55 attached to cross bars 48, having suitable eye bolts 49, by which the cage may be readily lifted from the vat. Extending across the cage 47, are vertical partitions 50, which are 60 formed of frames carrying screens so that the dye liquor may readily pass from one compartment to another. By these vertical partitions we have divided the cage into four main compartments. It will be obvious, however, that the number of vertical

partitions may be varied if desired. Each compartment is further divided by horizontal cross partitions 51, which are also formed of suitable frames supporting screens. These screen partitions 51, are hinged by 70 suitable pivot rods 52, and when in normal position, said hinge partitions rest on cleats 53, which are eccentrically mounted on a supporting rod 54, having a lateral projecting arm 55, (see Fig. VII).

75 Pivot latches 56, are provided for co-operating with the arms 54, see Fig. V, for holding the cleats in proper position for normally supporting the free end of the horizontal partitions. A cleat 57, is attached to 80 the side walls of the basket or cage, and serves as a stop against which the free edge of the screen partition is held by the supporting cleat 53.

85 A screen door 58, closes the top of each compartment and rests on a supporting strip 59. A latch 60, is adapted to hold said screen door in closed position. A second screen door 61, closes the bottom of each compartment and is held in closed position 90 by a cleat 62, which is similar to the cleat 53, and carries an arm 55, adapted to be locked by the swinging latch 56. It will thus be seen that we have provided a supporting cage or basket which is not only 95 formed with separated vertical compartments, but which is also formed with separated horizontal compartments so that the material to be dyed may be placed in comparatively small quantities in said 100 compartments and said material will be held separated during the treatment. When the material is wet or saturated with the dye liquor, it lies closer together, than when dry and is far less bulky, therefore 105 when the dye liquor is being forced upwardly through the cage, the material which is in the lower pockets will be forced against the central partitions and the material which is in the upper pockets will be forced against 110 the top closing doors and away from the central partitions. There is consequently some open space formed between the top of the material in the lower pocket or compartment, and the bottom of the material in the 115 upper pocket, or compartment, and this open space will be filled with the dye liquor.

120 The top screen door of each compartment may be readily lifted for convenience in loading the cage and likewise the lower screen doors may be released and dropped downward so that access may be readily had to the lower compartment. Underneath the grid 46, is a steam pipe 71, which may be fed with steam for the purpose of heating 125 the dye liquor.

130 By our construction wherein the material or articles to be dyed are placed in small quantities, in separate compartments, we are able to subject the material or articles being

dyed to an even flow of the dye liquor. Also by our construction wherein the operating shaft for the propeller extends through the side wall of the vat, we are able to do away 5 with the use of bevel gears in transmitting power to the propellers, which bevel gears would of necessity be located in the dye liquor, and thus reduce to a minimum the amount of metal which is exposed to the dye 10 liquor. We have also provided a mechanism wherein the propellers always run in the same direction, and wherein one propeller takes up the lateral thrust of the other propeller, and furthermore, the opposed propellers will cause the central circulation of 15 the dye liquor through the vat so as to produce a uniform flow through the various parts of the cage holding the dyed material.

The partition 3, as herein shown, is hinged 20 as at 45, and may be held in closed position by any suitable means. By the removal of the basket or cage and the grid 46, we are able to swing the partition 3, to the position shown in dotted lines in Fig. I, which will 25 afford a ready access to the propeller chamber so that the same may be cleaned or cleared of any particles of material accumulated therein and clogging the free flow of the dye liquor.

30 It is obvious that minor changes in the details of construction and the arrangement of the parts may be made without departing from the spirit of the invention as set forth in the appended claims.

35 We claim:—

1. A dyeing machine including in combination, a vat; means for circulating a dye liquor through said vat; and a cage for the material being dyed, said cage having a vertical partition forming separated vertical compartments, a horizontal partition forming horizontal compartments, said partitions being formed with screens, whereby the free flow of the dye liquor may be 40 had from one compartment to another, and hinged doors having screens therein for closing the top and bottom compartments; and movable securing means extending across the free edge of each bottom door for holding the same in closed position.

2. A dyeing machine including in combination, a vat; means for circulating a dye liquor through said vat; and a cage for the 45 material being dyed, said cage comprising a rectangular frame having vertical partitions therein which are formed with screens; a horizontal partition located intermediate the top and bottom of the frame and hinged at 50 one side so that the same may be readily opened; means for holding said partition in closed position; a hinged door at the top of the frame for each compartment; and a hinged door at the bottom of the frame for 55 each compartment; swinging cleats extend-

ing across each door for holding the same in closed position, arms carried by the cleats, and latches co-operating with said arms for locking the cleats to hold the doors closed, said doors and said partitions having screens 70 formed therein whereby a free flow of the dye liquor may be had through said compartments.

3. A dyeing machine including in combination, a vat; spaced partitions extending 75 across said vat which terminate short of the bottom and top of the vat, whereby a propeller chamber is formed with passages extending around the same; means for closing the top and the bottom of the propeller chamber and for forming a discharge opening at the top and at the bottom of said chamber; swinging valves for controlling said discharge openings; means whereby said valves may be alternately held in open position, said valves when in open position serving to deflect the dye liquor and thereby aid in causing an even circulation thereof; intakes 80 adjacent to each end of said propeller chamber leading to the passage in the rear thereof; and propellers located within said chamber and adjacent said intake, said propellers being opposed to each other.

4. A dyeing machine including in combination, a vat; spaced partitions extending 85 across said vat which terminate short of the bottom and top of the vat, whereby a propeller chamber is formed with passages extending around the same; means for closing the top and the bottom of the propeller chamber and for forming a discharge opening 90 at the top and at the bottom of said chamber; swinging valves for controlling said discharge openings; means whereby said valves may be alternately held in open position, said valves when in open position serving to deflect the dye liquor and thereby aid in causing an even circulation thereof; intakes 95 adjacent to each end of said propeller chamber leading to the passage in the rear thereof, propellers located within said chamber and adjacent said intake, said propellers being opposed to each other; and a horizontal shaft on which said propellers are 100 rigidly mounted, said horizontal shaft extending through one wall of the vat whereby 105 the operating mechanism therefor may be located outside of said vat.

5. A dyeing machine including in combination; a vat; spaced partitions extending 110 across said vat and forming a propeller chamber; means for closing the top and bottom of said propeller chamber and for forming discharge openings at the top and bottom of said chamber; valves for controlling 115 said openings; propellers located within said chamber; intakes leading to said chamber adjacent to said propellers, one of said partitions being hinged whereby the same 120 may be swung so that access may be had to 125

the chamber for cleaning or clearing the same.

6. A dyeing machine including in combination, a vat; a vertical partition extending 5 across said vat and terminating short of the top and bottom of said vat; a horizontal grid extending from said partition to one end of said vat and spaced from the bottom of the vat; a second partition spaced from 10 said first partition and from the opposite end of the vat whereby a propeller chamber is formed between said partitions and a circulating passage is formed between said chamber and the end wall of the vat; plates 15 for partially closing the top and bottom of said propeller chamber and for forming discharge openings at the top and bottom of said chamber, said propeller chamber having intakes adjacent to each end thereof; 20 opposed propellers located in the chamber adjacent to said intakes; and swinging valves for controlling the discharge from said propeller chamber, said swinging valves, when in open position, serving to 25 deflect the dye liquor and thereby aid in causing an even circulation thereof.

7. A dyeing machine including in combination, a vat; a propeller chamber in said

vat having discharge openings at the top and bottom thereof; valves for controlling 30 said openings; means for operating said valves including a rock arm having a substantially flat face; and a cam disk having a radial face coöperating with the rock arm, whereby the valves may be quickly shifted 35 from one position to another.

8. A dyeing machine including in combination, a vat; a propeller chamber located therein and having discharge openings; 40 valves for controlling said discharge openings; means for periodically shifting said valves including a cam; a shaft; gearing connecting said shaft with said cam, said gearing including a clutch whereby said shaft may be disconnected from said cam; 45 and a hand wheel for manipulating the cam when it is disconnected from the shaft.

In testimony whereof, we have hereunto signed our names at Philadelphia, Pennsylvania, this thirteenth day of January 1911. 50

WALTER W. SIBSON.
THOMAS ALLSOP.
